(57) **CLAIM**

What is claimed is the ornamental design for a “wine dispenser,” as shown and described.

DESCRIPTION

FIG. 1 is a front perspective view showing the “wine dispenser” of Applicant’s invention.

FIG. 2 is a front elevation view showing the “wine dispenser” of Applicant’s invention.

FIG. 3 is a back elevation view showing the “wine dispenser” of Applicant’s invention.

FIG. 4 is a left side elevation view showing the “wine dispenser” of Applicant’s invention.

FIG. 5 is a right side elevation view showing the “wine dispenser” of Applicant’s invention.

FIG. 6 is a top view showing the “wine dispenser” of Applicant’s invention; and,

FIG. 7 is a bottom view showing the “wine dispenser” of Applicant’s invention.

In the Figures, the dashed lines represent portions of the environment and surroundings and do not form part of the claimed invention.
